CASING FOR SPRAY DISPENSER

Robert E. Kirby, Charlotte, N.C., assignor to
General Time Corporation

Filed Nov. 5, 1973, Ser. No. 413,049

Term of patent 14 years

Int. Cl. D23—99

U.S. Cl. D23—150

FIG. 2.

FIG. 1.

FIG. 3.

FIG. 4.

FIG. 5.

FIG. 6.

FIG. 1 is a perspective view of a casing for spray dispenser showing my new design;

FIG. 2 is a front elevation of the casing of FIG. 1;

FIG. 3 is a side elevation of the casing of FIG. 1;

FIG. 4 is a rear elevation of the casing of FIG. 1;

FIG. 5 is a top plan view of the casing of FIG. 1; and

FIG. 6 is a bottom plan view of the casing of FIG. 1.

I claim:

The ornamental design for a casing for spray dispenser, substantially as shown.
